UNITED STATES PATENT OFFICE.

ARTHUR HOSMER, OF CHICAGO, ILLINOIS, ASSIGNOR OF ONE-FOURTH TO GUILFORD S. WOOD, OF CHICAGO, ILLINOIS.

OVERALLS.

Application filed December 15, 1922. Serial No. 607,031.

To all whom it may concern:

Be it known that I, ARTHUR HOSMER, a citizen of the United States, and a resident of the city of Chicago, in the county of Cook and State of Illinois, have invented certain new and useful Improvements in Overalls; and I do hereby declare that the following is a full, clear, and exact description of the same, reference being had to the accompanying drawings, and to the numerals of reference marked thereon, which form a part of this specification.

This invention is an improvement in the overalls shown in Patent No. 1,345,779, granted to me July 6th, 1920.

It is an object of this invention to produce the front and rear portions of a garment separately and unite them by seams which pass up the sides of the legs and down the sides of the sleeves.

It is a further object of this invention to provide a supporting loop for the belt which can be made more quickly and inexpensively than heretofore.

Other and further important objects of the invention will be apparent from the description in the following specification and the disclosures in the accompanying drawings, in which I have described and illustrated a preferred form of the invention.

On the drawings:

Figure 1 is a side view of the finished garment.

Figure 2 is a rear view.

Figure 3 is a section upon the line 3—3 of Figure 1.

Figure 4 is a section upon the line 4—4 of Figure 1.

Figure 5 is a detail illustrating the fastening of the belt.

As shown on the drawings:

The garment consists of an upper or blouse portion 1 and a nether or trousers portion 2. I have illustrated the form in which the blouse opens in front and the back is closed from the neck to the crotch by the seam 3. It will, however, be apparent as the description proceeds that the invention is equally applicable to a form in which the blouse buttons down the back and the front is made with a central seam or even in one piece.

The back of the garment is provided with a seat flap 5 which may be opened by being

let down into the position illustrated at 5' in dotted lines. A belt 10 is used to support the seat flap in closed position. This belt may be separately made and sewed to the upper edge of the flap or the hem at the top of the flap may be made to constitute the portion of the belt along said edge. The belt extends beyond the side edges of the flap in each direction and passes around to the front of the garment, where it is secured by any suitable fastening.

The fastening, illustrated in Figure 5, comprises a hook 11 which is held in a loop at one end of the belt. The loop is made adjustable by means of a sliding buckle 12. On the other end of the belt an eye 13 is secured, preferably by means of another loop and buckle.

The garment is provided with any desired number of pockets. As illustrated, there are a breast pocket at 6, a pair of hip pockets at 7 and 8 which are formed upon the above-described seat flap, and a rule pocket at 9.

As will be described below in detailing the method of making the garment, a single seam 15 on each side goes from the ankle opening up the side past the arm hole and through the wrist opening. This seam may be of any desired type. One common practice which may be used is to fold the edge of each of the two pieces which are to be secured together and then stitch through all four thicknesses. I have illustrated, however, a seam made by sewing a strip of tape to such folded edges.

A very desirable way of securing the belt 10 in place is illustrated in Figures 3 and 4. The seam 15 is cut away from the front portion 16 of the blouse part of the garment and from the rear portion 17 thereof through a distance slightly more than the width of the belt. This enables the separated part of the seam to be moved out of the plane of the cloth, and the belt 10 is passed through said separation. A loop for holding the belt in place is thus made without the necessity of separately preparing any piece of material to make the loop. The cut edges 18 and 19 of the main body of the cloth are protected from raveling in any desired way. The cut edges on the seam need no such protection because the folding and stitching made in forming the seam sufficiently prevent raveling.

In assembling the garment the several parts of the front are sewed together and the back of the blouse is sewed to the front along the shoulder seams. The sleeves, not yet closed into a tubular form, are then sewed to the arm-hole edges of the united front and back. The garment is then folded along the shoulders and sleeves, bringing the side edges of front and back of the blouse together and the edges of each sleeve together. A seam 24 is then run from each wrist opening to the arm-hole seam, across said seam and down the side of the blouse. It unites the edges of the blouse as far as the point 20. From here to the bottom 21 of the back of the blouse the edges of the front and back are left separated to provide a fent enabling the tail of the blouse to hang loose, like the tail of a shirt.

23 The edges of this fent may be finished in any usual way. Since a better appearance is secured if the edge of the front part of the blouse is placed outside, it is convenient to have the same seam that goes down the side of the blouse continue as the seam uniting the finishing tape to the front side of the fent, as shown at 22.

30 The side edge of the seat flap in closed position lies close to this fent. It is of course free from the neighboring edge of the front part of the garment in order that it may be moved to dotted line position. This neighboring edge of the front part is the front edge of the fent already described. 35 The tape or other finish 22 for this edge may therefore advantageously be continued up the inside of the edge of the seat flap.

40 The two edges protected by this one continuous finish outline a placket from the bottom of which goes a seam 15 which, except as it is interrupted by the placket, is continuous with the seam 24. As the placket edges are finished by sewing, one continuous line of sewing extends from the 45 wrist opening to the ankle opening. Preferably the side seam is sewed from the ankle opening to the bottom of the placket. Then the seam is started again from the top of the edge of the seat flap past the upper end of the seam just mentioned and past the arm-hole seam to the wrist opening.

50 A continuous seam extends from one ankle opening to the other across the crotch. This may be sewed either before or after the continuous lines of sewing described above.

55 I am aware that numerous details of construction may be varied through a wide

range without departing from the principles of this invention, and I therefore do not purpose limiting the patent granted 60 otherwise than necessitated by the prior art.

I claim as my invention:

1. In an overalls, a blouse portion and a nether portion, a seat flap extending from said nether portion over the outside of the bottom of the back of the blouse portion, a belt for securing said flap in position, and seams up each side of the overalls uniting the front and back sections thereof, said seams being separated from the body of the 70 garment by slits for said belt.

2. In an overalls, a blouse portion having on each side a fent separating a tail from the front of the garment, a nether portion having a seat flap, edge finishing seams one 75 along each side edge of said seat flap and extending along the edges of the fent, seams one on each side from the top of said fent to the wrist opening, and seams one on each side from the bottom of said fent to the 80 ankle opening whereby said side seams and edge finishing seams on one side make one continuous seam from the ankle to the wrist.

3. In an overalls, a blouse portion having on each side a fent separating a tail from the front of the garment, a nether portion having a seat flap, edge finishing means one along each side edge of said seat flap and extending along the edges of the fent, 85 seams one on each side from the top of said fent to the wrist opening, and seams one on each side from the bottom of said fent to the ankle opening whereby said side seams and edge finishing seams on one side make one 90 continuous seam from the ankle to the wrist, said seams being cut away from the garment 95 above said fent to provide loops, and a belt attached to said seat flap and adapted to pass through said seam loops.

4. In an overalls, a blouse portion and 100 nether portions having a seat flap, a seam extending upwardly along the side of the garment, said seam being cut away from the garment to provide a pair of slits in said blouse portion, and a belt through said slits 105 for supporting said seat flap.

In testimony whereof I have hereunto subscribed my name in the presence of two subscribing witnesses.

ARTHUR HOSMER.
